UNITED STATES PATENT OFFICE.

JOHN F. GUBBINS, OF CHICAGO, ILLINOIS.

DRIVING MECHANISM FOR WASHING-MACHINES.

1,294,448.

Specification of Letters Patent. Patented Feb. 18, 1919.

Application filed April 17, 1915. Serial No. 22,083.

To all whom it may concern:

Be it known that I, JOHN F. GUBBINS, a citizen of the United States, residing at Chicago, in the county of Cook and State 5 of Illinois, have invented certain new and useful Improvements in Driving Mechanism for Washing-Machines, of which the following is a specification.

This invention relates to an improved 10 driving mechanism for washing machines.

The principal object of my invention is to provide an improved mechanism for continuously driving the rotating cylinder of the washing machine, and intermittently reversing the direction of rotation thereof. A further object is to provide an improved 15 gearing device for continuously driving the rotating cylinder and automatically reversing the direction of rotation. Another object is to provide improved means for supporting the driving mechanism, together with means for protecting certain parts of the mechanism. I also provide means for connecting the cylinder rotating mechanism 20 to drive the wringer shaft when desired, and improved means for rendering the mechanism inoperative with respect to the cylinder of the washing machine. Still another object relates to the combination of means 25 for driving the rotating cylinder with means for permitting the cylinder to be readily withdrawn from the remainder of the washing machine when desired. Another object is to provide improved means 30 for maintaining efficient action of the motor which actuates the driving mechanism.

These and other objects of the invention will appear more clearly in the following 35 specification, taken in connection with the accompanying drawings, in which I have illustrated one embodiment of the invention.

In the drawings—

Figure 1 shows an end elevation of the 40 washing machine with my improved driving mechanism supported in operative relation thereto, the cover of the gear housing being removed.

Fig. 2 is a side elevation of the same, certain parts being broken away.

Fig. 3 is a sectional view, taken on the line 3—3 of Fig. 1.

Fig. 4 is a detail sectional view, taken on the line 4—4 of Fig. 1.

Fig. 5 is a sectional view taken on the line 55 5—5 of Fig. 1.

Fig. 6 is a sectional view taken on the line 6—6 of Fig. 2.

Fig. 7 is a sectional view taken on the line 7—7 of Fig. 2.

Fig. 8 is a perspective view of the load 60 shaft which actuates the cylinder; and

Fig. 9 is a perspective view of a portion of the bracket member which is attached to the end of the cylinder and arranged to co- 65 act with the shaft shown in Fig. 8.

Referring to the drawings, the washing machine, designated generally by the numeral 10, is shown as comprising a tank 11, the lower portion of which is semi-cylindrical in form, and which is closed at the ends by the end walls 12 and 13. The tank is supported by legs 14 and 15, which extend downwardly from the corners of the tank at opposite ends, respectively. These legs 70 are preferably of angle-iron form, and the legs of each pair 14—15 are connected adjacent their lower extremities by means of angle brace bars 16. The lower end of each leg is operatively connected to a roller or 80 caster 17, whereby the washing machine may be readily moved to the desired position.

In Fig. 2 of the drawings the tank and 85 angle bars 16 are shown as being broken between their extremities, to indicate that these parts may be made of any desired length. A faucet 18 is connected to the lower portion of the tank at one end thereof to permit the withdrawal of water, or other 90 contents of the tank.

The rotating cylinder 20, adapted to contain clothes to be washed, is mounted within the tank, and is supported in bearings at each end thereof, to rotate concentrically 95 with the lower semi-cylindrical portion thereof. At the right hand end, as viewed in Fig. 2, the cylinder 20 has secured to the middle portion of its end wall a bracket which carries a stub shaft 21, which is 100 adapted to rotate in the journal formed by the lower portion of the outwardly extending flange 22 of a U-shaped bracket 23 secured to the end wall 13 of the tank. A vertically extending slot 24, formed between 105 the opposite portions of the flange 22, permits the removal of the cylinder and the outwardly flared upper extremities of the

bracket 23 to guide the stub shaft into position in said slot. For a purpose to be hereinafter set forth, the flange 22 projects inwardly toward the cylinder at opposite sides of the bearing, as shown at 22^a.

At its other end the cylinder has secured thereto a bracket 25, which is in alignment with the stub shaft 21, and which has formed thereon a V-shaped lug 26, upon which is formed a curved surface 27. This lug is adapted to engage and closely fit the V-shaped slot 28, which extends radially inward from the periphery of the cylindrical block 29 formed on the end of the load shaft 30, which is adapted to be driven by my improved driving mechanism. When the lug 26 is in position in the slot 28, the curved surface 27 is adapted to form a continuation of the peripheral surface of the cylindrical block 29. The cylindrical block is journaled in the lower portion of a bracket 31, which is secured to the end wall 12 of the tank 11, and the upwardly extending arms of said bracket are spaced apart to form a guide or slot 32 of substantially the same width as the widest portion of the V-shaped lug 26, so that said V-shaped lug may be passed vertically in the slot 32, when it is desired to withdraw the cylinder from the tank. The slot 32 is closed a short distance from the end of the bearing by a lug 32^a, so that after the lug 26 has been lowered in the slot 32 below the lug 32^a the movement of the cylinder toward the end wall 12 will bring the lug 26 beneath the lug 32^a to prevent the displacement thereof from the slot 28. When the cylinder is lowered into the tank, the lug 26 is first lowered into alignment with the load shaft, after which the other end of the cylinder is lowered, and the inclined surfaces 22^a engaging the bracket of the shaft 21 will move the cylinder longitudinally and cause the lug 26 to engage the slot 28 below the lug 32^a.

My improved driving mechanism, now to be described, comprises a supporting frame 35, which is secured to the legs 14 by bolts, or other suitable means, at the points 36, 37, 38, and 39. The upper portion of the supporting frame comprises a transverse plate 40, which has integrally formed therewith, adjacent its middle portion, a cylindrical sleeve 41, which extends inwardly through the wall 12 of the tank concentrically with the load shaft 30 previously described. The sleeve 41 communicates with an outwardly projecting sleeve 42 of smaller diameter. Seated in the sleeve 42 is a stuffing-box bushing 43, which is enlarged within the sleeve 41 to form a stuffing chamber 44 adapted to contain packing material. The packing nut 45 threadedly engages the walls of the stuffing chamber, and is retained in the desired position by a spring clip 46, which engages a notch in the annular flange

of said nut. This spring clip is secured to the sleeve 41 by a screw 47, which also engages the bushing 43 and maintains the same in position. The load shaft 30 is journaled in the packing nut 45, and the reduced part 70 of the bushing 43, as shown, for instance, in Fig. 2, and the outwardly projecting extremity of said shaft has keyed or otherwise secured thereon a pinion 48.

The pinion 48 and load shaft 30 are 75 driven through intermediate mechanism from a power shaft 49, which is journaled in the hub portions 50 and 51 carried by the lower portion of the frame 35. This power shaft projects inwardly from the hub portion 50 toward the end wall 12 of the tank. Secured to this projecting extremity by a pin, or other suitable means, is the relatively large pulley wheel 52, which is adapted to be driven by a belt 53 from the 80 motor 54. This motor is secured to a supporting base 55, which is slidably mounted on the oppositely disposed angle bars 16 of the washing machine frame. Each of the angle bars has secured thereto, at each side 85 of the supporting base 55, a Z-bar clip 56, which extends upwardly and engages a lateral edge and a portion of the top surface of the base 55. These Z-bar clips serve to guide the base for a sliding movement 90 on the angle bars 16. An I-bolt 57 engages the depending flange of the angle bar 16 adjacent the middle portion of the motor 54, and a coil spring 58 is secured to this I-bolt at one extremity, and is connected at its other extremity to an I-bolt 59 which is secured to the motor base 55 at the opposite side of the motor from the I-bolt 57. The coil spring 58 is normally in tension and serves to tend to slide the motor base 55 to the right, as viewed in Fig. 1, thereby serving to tighten the belt 53 and prevent slipping thereof on the driving wheel of the motor or on the V-shaped periphery of the pulley wheel 52.

The power shaft 49 has keyed thereon, between the hub portions 50 and 51, a worm 65, which is adapted to coact with a worm wheel 66 secured to the lower portion of a transverse upwardly extending transmitting shaft 67, which is journaled in the alining hub portions 68, 69, 70, and 71 formed integrally with the supporting frame 35. Each of the hub portions is provided with a bushing of Babbitt metal, or the like, as 115 shown clearly in Fig. 1. As the worm 65 coacts with the worm wheel 66, the thrust, which reacts through the worm, is received by a ball-bearing thrust collar 72, which is mounted on the shaft 49 between said worm 120 and the hub portion 50.

The hub portions 68, 69, 70, and 71, above described, are formed within a housing 73, which forms a part of the frame 35, and the cover portion 73^a of this housing, which 130

carries the hub portion 51 above described, is removable from the inner integral portion of the housing, and is attached thereto by screws 74, or other similar means. The hub 5 of the worm wheel 66, which is pinned or otherwise secured on the transmitting shaft 67, is adapted to coact with the upper extremity of the hub portion 68, and is located between said hub portion and the hub 10 portion 69, whereby displacement of the worm wheel 66 and the shaft 67 is prevented.

A ball bearing thrust collar 75 is mounted upon the shaft 67 above the hub portion 70, and coacting with this thrust collar and rotatably mounted on the transmitting shaft 67 is a worm 76, which has ratchet teeth 77 formed upon the upper end face thereof. These ratchet teeth are adapted to coact with similar ratchet teeth formed upon the 20 end of a cylindrical ratchet member 78, which is splined upon the shaft 67 by means of a feather 79. The ratchet member 78 is journaled in the hub portion 71 of the housing 73, and the annular flanges 80 of 25 said clutch member are adapted to coact with lugs carried at the extremities 81 of the clutch lever 82, which is pivotally mounted on the frame 35 at 83. When the clutch lever is moved outwardly the clutch 30 member 78 will move downwardly on the shaft 67 into engagement with the worm 76, whereupon said worm will be connected to rotate with the transmitting shaft 67.

The worm 76 is adapted to drive a worm wheel 85, which is keyed upon the intermediate short shaft 86, journaled in the bearing portions 87 and 88 of the housing 73. The inner extremity of the shaft 86 projects beyond the bearing portion 87 of the 40 housing, and has secured thereto, by a pin, or other similar means, a crank arm 89. The other end of this crank arm is pivotally connected to a connecting rod or link 90, which terminates at its other end in two 45 parallel plates 91 which extend on opposite sides of the arm 92 of the geared sector 93. A pin 94 passes through the plates 91 and the arm 92 to form a pivotal connection between the connecting rod and said arm. The 50 rack teeth 95 of the geared sector 93 are formed on the under side of an inwardly extending arcuate flange 96, and said teeth are adapted to mesh with the teeth of the pinion 48 fixed on the load shaft 30. The lower 55 extremity of the arm 92 of the geared sector is located between the bearing portions 97 and 98 of the frame 35, and a pivotal connection is formed therewith by means of the pin 99.

It will be seen that the rotation of the intermediate shaft 86 will operate to reciprocate the connecting rod 90, and thereby transmit a similar motion to the geared sector, so that the load shaft will be rotated alternately in opposite directions during the

rotation of the shaft 67. The parts are so arranged that the geared sector will be in its extreme positions with respect to the pinion 48, and said pinion comes to rest when the crank arm 89 is in its head center 70 and dead center positions with respect to the connecting rod 90.

Mounted upon the upper portion of the washing machine is a housing 100 provided with an offset arm 101, having transverse flanges 102, which are secured to the end wall of the tank. The transmitting shaft 67 extends upwardly into the housing and is journaled in the bearing portions 103 and 104 of said housing. Rotatably mounted on said shaft 67, within the housing 100, are two oppositely disposed bevel gear pinions 105 and 106, which have ratchet teeth 107 formed on their inner adjacent faces. Each of the bevel gear pinions 105 and 106 is arranged to mesh with a bevel gear 109, which is pinned, or otherwise fixed, on a wringer driving shaft 110 journaled in the bearing portion 111 of the housing 100. The projecting extremity of the shaft 110 carries a 85 clutch member 112, which is adapted to engage a complementary clutch member carried by a wringer shaft. Splined on the transmitting shaft 67, between the bevel gear pinions 105 and 106, is a clutch sleeve 115, 90 which has clutch teeth formed on the opposite end faces thereof adapted to coact with the clutch teeth 107 previously described. An annular groove 116, formed in the clutch sleeve, is adapted to be engaged by the lug 117 formed on the projecting arm of a bell crank operating lever 119, which is pivotally mounted in the wall of the housing. The lever 119 may be operated to reciprocate the clutch member 115 on the shaft 67 100 to engage the clutch teeth carried by either of the bevel gear pinions 105 or 106, thereby forming a non-rotative engagement between either of said bevel gear pinions and the transmitting shaft 67, whereupon the 105 wringer shaft will be driven in the desired direction through the wringer driving shaft 110. The housing is provided with an opening in its front face, which is closed by a pivotally mounted door 120. This door may be 110 radially swung into open position to permit access to the gears contained within the housing, and is supported in closed position by a lug 121.

In the operation of the device, the clothes 120 are placed in the cylinder 20, which is adapted to rotate in the tank 11 containing water or other washing fluid. After starting the motor 54, so as to drive the power shaft 49 through the belt 53, the clutch lever 82 is 125 moved upwardly so as to cause a downward movement of the clutch member 78, whereupon a non-rotative engagement will be formed between the worm 76 and the transmitting shaft 67, which is driven through 130

the worm wheel 66 and worm 65. The clutch member 78 and clutch lever 82 are so balanced and arranged as to be retained in either operative or inoperative positions.

- 5 After moving the clutch lever upwardly as described, the worm 76 will operate to drive the intermediate shaft 86, whereupon the crank arm 89 will be rotated and a reciprocating angular movement will be imparted 10 to the geared sector 93. As the geared sector moves alternately in opposite directions, the pinion 48 and load shaft 30 will be rotated continuously and be automatically reversed in the direction of rotation when the 15 geared sector reaches either limit of its travel.

When it is desired to connect the transmitting shaft 67 for driving the shaft of a wringer supported upon the upper part of 20 the washing machine, the operating lever 119 may be manipulated, as previously described, to cause the wringer driving shaft 110 to be rotated in the desired direction. When the wringer shaft is being driven the 25 clutch member 78 may, if desired, be rendered inoperative, thus discontinuing the rotation of the cylinder 20.

From the foregoing description it will be apparent that a number of the gears of the 30 driving mechanism are contained within the housing 73, and that the gears of the wringer driving clutch mechanism are contained within the housing 100. These gears are thus protected from dirt and moisture, 35 and at the same time access may be readily gained to the interior of these housings by removing the cover 120 and cover portion 73a. It will further be apparent that the pinion 48 and rack teeth 95 are protected by the trans- 40 verse outwardly extending flange of the plate 40 of the member 35.

It will be seen that all of the parts of my improved driving mechanism are carried by the frame 35 of novel form and arrangement 45 of parts. During the operation of the driving mechanism the coil spring 58 operates continuously to maintain a tight, frictional contact between the belt 53 and the pulley wheel 52, and the motor-driving wheel with 50 which it coacts.

Although I have shown and described a particular embodiment of the invention, it will be understood that I contemplate changes in form and arrangement of parts 55 as circumstances may suggest, or necessity require, without departing from the scope of the invention as defined in the appended claims.

I claim:—

- 60 1. In an improved gearing device, a power shaft, an upwardly extending transmitting shaft driven by said power shaft, an intermediate shaft adapted to be driven by said transmitting shaft, a horizontal load shaft,

and means actuated by said intermediate 65 shaft for imparting an alternating rotary motion to the load shaft.

2. In an improved gearing device, a power shaft, a transmitting shaft driven by said power shaft, an intermediate shaft adapted 70 to be driven by said transmitting shaft, a reciprocating rack member driven by said intermediate shaft, a load shaft, a pinion fixed on said load shaft and arranged to be driven by the rack member, and a frame 75 member in which all of said shafts are journaled.

3. In an improved gearing device, a power shaft, a transmitting shaft driven by said power shaft, an intermediate shaft adapted 80 to be driven by said transmitting shaft, a geared sector pivoted on a horizontal axis and extending upwardly therefrom, means driven by the intermediate shaft to reciprocate said geared sector about its pivotal axis, a horizontal load shaft, and a pinion fixed on said load shaft and arranged to mesh with the 85 geared sector.

4. In an improved gearing device, a power shaft, an upwardly extending transmitting 90 shaft driven by said power shaft, an intermediate shaft adapted to be driven by said transmitting shaft, a reciprocatory member pivotally mounted on a horizontal axis and extending upwardly from said axis, said 95 reciprocatory member having an arcuate flange projecting therefrom with rack teeth formed on the underside of said flange, a crank fixed on said intermediate shaft, a link pivotally connected to said crank and to said reciprocatory member giving the latter a reciprocating motion, a horizontal load shaft, and a pinion fixed on said load shaft to mesh with said rack teeth. 105

5. In an improved gearing device, an upwardly extending supporting structure, a frame member secured to the side of said supporting structure, a power shaft journaled in said frame adjacent the lower part 110 thereof, a transmitting shaft driven by said power shaft and extending upwardly therefrom, said transmitting shaft being journaled in said frame, a horizontal intermediate shaft journaled in said frame and arranged to be driven by said transmitting shaft, a horizontal load shaft journaled in said frame, and means actuated by said intermediate shaft for driving said load shaft. 115

6. In an improved gearing device, an upwardly extending supporting structure, a frame member secured to the side of said supporting structure, a load shaft journaled in said frame, an intermediate shaft journaled in said frame, a transmitting shaft journaled 125 in said frame, gearing devices for operatively connecting said shafts, a housing formed integrally with said frame for im-

closing said gearing devices, a load shaft, and means actuated by said intermediate shaft for driving said load shaft.

7. In an improved gearing device, a power shaft, a worm fixed on said shaft, a transverse upwardly extending transmitting shaft, a worm wheel fixed on said transmitting shaft, an intermediate shaft, a worm wheel fixed on said intermediate shaft, a worm mounted on said transmitting shaft and adapted to mesh with the worm wheel on the intermediate shaft, means to form a non-rotative engagement between said last-mentioned worm and said transmitting shaft, a load shaft, and operating connections from said intermediate shaft to impart rotation to said load shaft.

8. In an improved gearing device, a power shaft, a worm fixed on said shaft, a transverse upwardly extending transmitting shaft, a worm wheel fixed on said transmitting shaft, an intermediate shaft, a worm wheel fixed on said intermediate shaft, a worm mounted on said transmitting shaft and adapted to mesh with the worm wheel on the intermediate shaft, a clutch member slidably and non-rotatably mounted on the transmitting shaft above said last-mentioned worm, means to cause said clutch member to engage clutch teeth formed on the last-mentioned worm, a load shaft, and means actuated by said intermediate shaft for imparting rotation to said load shaft.

9. In an improved gearing device, a horizontal power shaft, a worm fixed on said shaft, a transverse upwardly extending transmitting shaft, a worm wheel fixed on said intermediate shaft to mesh with said worm, another shaft arranged adjacent said transmitting shaft, and clutch mechanism mounted on said transmitting shaft for operatively connecting the same with said last-mentioned shaft.

10. In an improved gearing device, a supporting structure, a frame carried by said supporting structure, a power shaft journaled in said frame, an upwardly-extending transmitting shaft journaled in said frame, an intermediate shaft journaled in said frame, a gearing device for transmitting motion from the power shaft to the transmitting shaft and from the transmitting shaft to the intermediate shaft, a load shaft, and means carried by said frame and actuated by the intermediate shaft for causing a continuous alternating rotation of said load shaft.

11. In an improved gearing device, a supporting structure, a frame carried by said supporting structure, a power shaft journaled in said frame, an upwardly extending transmitting shaft journaled in said frame, an intermediate shaft journaled in said frame, a gearing device for transmitting motion from the power shaft to the trans-

mitting shaft and from the transmitting shaft to the intermediate shaft, a housing carried by said frame for inclosing said gearing device, a load shaft, and means carried by said frame and actuated by the intermediate shaft for causing a continuous alternating rotation of said load shaft.

12. In an improved gearing device, a load shaft, means for imparting a rotary motion to said load shaft, a stub shaft in alignment with said load shaft and having a lug extending from the end thereof, said load shaft having a slot in its extremity adapted to receive said lug, and a relatively fixed member for preventing displacement of said lug from said slot during the rotation of said shafts.

13. In an improved gearing device, a load shaft, means for imparting a rotary motion to said load shaft, a stub shaft abutting against said load shaft, said stub shaft having a radially extending lug formed on the end thereof, said lug being adapted to enter a slot in said load shaft, and a bearing for the extremity of said load shaft, said bearing having a slot in the periphery thereof to permit the withdrawal of said lug from the slot in said load shaft.

14. In an improved gearing device, a load shaft, means for imparting a rotary motion to said load shaft, a stub shaft abutting against said load shaft, said stub shaft having a radially extending lug formed on the end thereof, said lug being adapted to enter a slot in said load shaft, a bearing for the extremity of said load shaft, said bearing having a slot in the periphery thereof to permit the withdrawal of said lug from the slot in said load shaft, and means to prevent such withdrawal when said stub shaft is in normal operative position.

15. In an improved gearing device, a horizontal power shaft, a transmitting shaft driven by said power shaft, an intermediate shaft adapted to be driven by said transmitting shaft, a geared sector pivoted on a horizontal axis and extending transversely thereto, means driven by said intermediate shaft to reciprocate said geared sector about its pivotal axis, a horizontal load shaft, and a pinion fixed on said load shaft and arranged to mesh with said geared sector.

16. In an improved gearing device, a vertically extending frame, a horizontal power shaft supported by said frame, an electric motor carried by said frame and connected by a belt driven by said power shaft, a transmitting shaft driven by said power shaft, a horizontal intermediate shaft adapted to be driven by said transmitting shaft, a geared sector having a supporting arm pivoted on a horizontal axis carried by said frame, means driven by said intermediate shaft to reciprocate said geared sector about its pivotal axis.

- a horizontal load shaft having a part projecting from said frame, and a pinion fixed on said load shaft and arranged to mesh with said geared sector.
- 5 17. In an improved gearing device, an upwardly extending supporting frame, a horizontal power shaft journaled in said frame, means for driving said power shaft, a horizontal intermediate shaft spaced from said power shaft, a transmitting shaft, speed-reducing gears for transmitting power from said power shaft through said transmitting shaft to said intermediate shaft, a member having a geared sector on one end and comprising a supporting arm pivoted on the side 15 of said frame to swing about a horizontal axis, a link pivotally connected to said crank arm and to an intermediate part of said member, a horizontal load shaft having its journal carried by said frame, and a gear 20 fixed on said load shaft and meshing with the geared sector carried by said member.
- 10 In testimony whereof, I have subscribed my name,

JOHN F. GUBBINS.
